UNITED STATES PATENT OFFICE

112,352

DESIGN FOR A PIANO CASE

Samuel E. Zack, Chicago, Ill., assignor to Gulbransen Company, Chicago, Ill., a corporation of Illinois

Application March 26, 1937, Serial No. 68,412

Term of patent 3½ years

To all whom it may concern:

Be it known that I, Samuel E. Zack, a citizen of the United States, residing at Chicago, in the county of Cook and State of Illinois, have invented a new, original, and ornamental Design for a Piano Case, of which the following is a specification, reference being had to the accompanying drawing, forming a part thereof, and in which:

Figure 1 is a perspective view of a piano case, in open position, showing my new design; and

Figure 2 is a side elevational view of the piano case of Figure 1, in closed position.

Each of the rear legs cut axially to provide a "half-leg" abutting and secured to the side wall of the piano case below the key bed and forwardly of the rear marginal edge of the aforementioned wall of the piano case, whereby the leg is clearly outlined against such wall, constitute the dominant features of my design.

I claim:

The ornamental design for a piano case, as shown and described.

SAMUEL E. ZACK.
